UNITED STATES PATENT OFFICE

2,329,326

CONVERTIBLE BATHING APPARATUS

Maxwell H. Bloomberg, Pittsburgh, Pa.

Application November 6, 1941, Serial No. 418,080

1 Claim. (Cl. 5—91)

The present invention relates to new and useful improvements in bathing apparatus designed primarily for use by bedridden patients, infants, and the like and has for its primary object to provide a shallow open tank having a bottom coextensive with a mattress on which the tank is positioned and adapted to contain a quantity of water for use in bathing purposes, the side walls of the tank being constructed of live rubber and capable of being folded downwardly along the sides of the mattress, when not in use as a bathing apparatus, to provide a protective cover for the mattress.

An important object of the present invention is to provide a bathing apparatus of this character adapted to be arranged in bathing position without necessitating removal of the patient from the mattress.

A still further object is to provide a device of this character of simple and practical construction, which is efficient and reliable in use, relatively inexpensive to manufacture and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which:

Figure 1 is a perspective view showing the tank in position on a mattress ready for use as a bathtub.

Figure 2 is a fragmentary vertical sectional view.

Figure 3 is a fragmentary top plan view of one corner of the device.

Figure 4 is a fragmentary horizontal sectional view of a corner of the tank showing the reinforcing corner rib.

Figure 5 is a perspective view of a modified form of the invention, and

Figure 6 is a transverse sectional view thereof.

Referring now to the drawings in detail and with particular reference to Figures 1 to 4 inclusive, the numeral 5 designates the shallow rubber tank or bathtub which includes a bottom 6 which is coextensive with a mattress 7 on which the tank is positioned, the tank including upstanding walls 8, the bottom 6 and walls 8 being constructed of live rubber.

A reinforcing beading 9 is formed around the bottom edges of the walls and a beading 10 is likewise formed around the upper edges thereof. The corners are likewise formed with a vertical rib 11 capable of providing sufficient strength to the walls to maintain the same in an upstanding

position when the tank is filled with a supply of water.

When the tank is not desired for use for bathing purposes, the side walls 8 are adapted to be folded downwardly along the sides of the mattress 7 as shown by the dotted lines in Figure 2 of the drawings, and the device is then retained on the mattress and used as a protective cover therefor. Under such circumstances the protective cover 5 may be covered by the usual sheet or other bed clothing and in using the device for bath purposes, it is only necessary that the sheet or other bedclothing be removed and the side walls 8 moved into their upstanding position, as shown 10 by the full lines in Figure 2, whereupon the device is ready for use for bathing the patient without necessitating the removal of the patient from the bed.

Projecting from one lower corner of the tank 20 is a flexible rubber tube 12 adapted to drain the contents of the tank into a suitable receptacle, the inner end of the tube being adapted to receive a plug 13 and the outer portion of the tube may be provided with a conventional form of clamp 14 25 adapted to cut off the flow of water therethrough in the usual manner.

In the form of the invention illustrated in Figures 5 and 6 of the drawings, the mattress 15 is constructed of rubber and to the upper surface 30 thereof the walls 16 of the tank are integrally molded, the tank thus being formed as an integral part of the mattress. In this form of the invention the drain tube 17 is likewise provided at one lower corner of the wall 16 and the walls are 35 provided at their upper edges with a beading and are provided at their corners with the vertical reinforcing ribs as heretofore explained.

From the foregoing it will be apparent that the invention provides convenient means for bathing 40 bedridden patients without the necessity of removing the patient from the bed and the device is also adapted for use in the treatment of incontinent patients by providing a protector and container carried by the bed from which the excretions may be drained.

It is believed the details of construction and manner of use of the device will be readily understood from the foregoing without further detailed explanation.

Having thus described the invention what I claim is:

A mattress including a rubber top and continuous wall of sheet rubber integral with the top and rising from the edges of the mattress and adapted for folding into a downwardly extending position with respect to the mattress to form a cover surrounding the sides of the mattress.

MAXWELL H. BLOOMBERG.
